UNITED STATES PATENT OFFICE.

ROBERT DOUGLAS MONCRIEFF, OF KINGSTON, ONTARIO, CANADA.

KNOCKDOWN TABLE.

Application filed March 11, 1927, Serial No. 174,673, and in Canada December 11, 1926.

This invention relates to tables and more particularly to camp tables of the knock-down type.

The particular object of this invention is 5 to provide a table wherein the various parts can be fitted into a most compact size and when opened out for use, may be easily fitted together in a tight and secure manner.

A further object of my invention is to provide 10 a table of the knock-down type, which table will have its side members retained in position by the end members.

A further object is to provide a table of 15 the knock-down type wherein the longitudinal side members and the cross end members are provided with a protruding ledge on their inner side, on which is retained the table top.

Other objects and advantages of my invention 20 will become apparent ensuing a perusal of the following specification read in conjunction with the annexed drawings, in which:

Fig. 1 is a perspective view of my invention 25 showing the table top in position, the flexible connecting straps being shown in dotted lines.

Fig. 2 is a perspective view of a section of 30 one of the end uprights, one of the end cross members and one of the longitudinal side members, parts being broken away.

Fig. 3 is a sectional view taken on the line 3-3 of Fig. 2.

Fig. 4 is a modified form of providing a 35 protruding ledge to receive the table top.

Like numerals of reference designate corresponding parts throughout the different views.

5 indicates corner posts preferably made 40 from angle-iron. On one side of the angle-iron, spaced tongues 6 are cut from the metal near the upper end, which tongues are bent inwardly at a right angle to the body portion of this side of the post. On the opposite 45 site side of the angle iron post 5, I provide an inwardly bent tongue 7, which extends outwardly at a right angle from the body portion of this side of the angle-iron post 5 and is then bent at right angles towards the 50 outer edge of this side of the angle post 5.

The longitudinal side members 8 are formed in two sections and hinged as at 9 so that these side members can be folded into a compact size. At the opposite ends of the 55 side members 8, openings 10 are formed, which openings correspond in size, position

and shape to register with and fit over the protruding tongues 6 in one side of the angle post 5 as hereinbefore described. 11 is cross end members provided at each end with 60 a cut out portion 12 on its under side, which portion 12 is adapted to fit over the outwardly directed portion of the tongue 7. The end of the cross end member 11 will abut the inner end of the longitudinal side member 65 8 and retain it in its fixed position on the tongue 6. The outer end of the tongue 7, which is bent parallel to this side of the angle-iron post 5, will retain the cross end member 11 against any inward movement. 70

The longitudinal side members 8 and the cross end members 11 are provided near their upper inner edge with a ledge 14. This ledge may be provided in any desired manner. In 75 Figs. 2 and 3, I have shown small strips of angle-iron, having one side riveted to the longitudinal side members 8 and the cross end member 11. I do not wish to limit myself to this particular construction as the material forming the longitudinal side members 8 and the cross end members 11 may be so bent, as shown in Fig. 4, as to provide 80 an inwardly protruding ledge 14^a.

15 is the table top preferably formed from cross slats, which may be secured together 85 by flexible strips 16, so that the slats may be rolled up into a compact arrangement. Furthermore, the flexible strips will keep the slats in order for readily positioning them to fit over the inwardly protruding ledges 90 14. The thickness of the slats 15 is preferably the same as between the ledge 14 and the upper edge of the longitudinal side members 8 or the cross end members 11. In this way, a flat upper surface will be provided. 95

From a perusal of the description taken in connection with the annexed drawings, it will be appreciated that I have provided 100 a simple construction wherein the fitting of the longitudinal side members and the cross end members to the angle-iron posts is simple, inexpensive and yet most effective.

The foregoing specification and annexed drawings discloses the preferred embodiment 105 of my invention, but it is to be understood that minor changes may be resorted to in the commercial adaptation of my invention without departing from the scope of the invention as hereinbefore claimed.

What I claim as new is:

1. In a table of the knock-down type com-

prising angle-iron corner posts; the upper end of one side of said angle-iron posts being provided with spaced inwardly directed tongues; longitudinal side members provided with spaced openings near their opposite ends fitted over said tongues; the other side of said angle-iron posts being provided with an inwardly directed tongue, the end of which is bent at right angles towards the outer edge of said side; cross end members, each provided with a slot formed in its under side near the opposite ends thereof, which slot is fitted over last said tongue; the ends of said cross end members abutting the inner ends of said longitudinal side members to retain the same in fixed position; said longitudinal side members and the cross end members being provided with ledges near their upper inner edges and 20 flexibly connected cross slats fitting on said ledges to form a top for said table.

2. In a table of the knock-down type comprising angle-iron corner posts; said posts being provided with spaced inwardly directed tongues on one side and an inwardly directed tongue, the end of which is bent outwardly at an angle, on the other side;

30 side members having openings fitted over said spaced tongues; cross end members having a slot near each end adapted to fit over said tongue; and the end of said cross end members abutting the ends of said side member to retain the same in fixed position; ledges in connection with said side members and end members; and a table top fitting on 35 said ledges.

3. In a table of the knock-down type comprising angle-iron corner posts; said posts being provided with spaced inwardly directed tongues on one side and an inwardly 40 directed tongue, the end of which is bent outwardly at an angle, on the other side; side members having openings fitted over said spaced tongues; cross end members having a slot near each end fitted over said tongues; 45 and the ends of said cross end members abutting the ends of said side member to retain the same in fixed position; a top for said table and a means of supporting said top from said side members and end members.

In testimony whereof, I affix my signature.

ROBERT DOUGLAS MONCRIEFF.
